UNITED STATES PATENT OFFICE.

WILLIAM H. CURRY, OF BALTIMORE, MARYLAND.

DESIGN FOR A SOUVENIR.

SPECIFICATION forming part of Design No. 13,044, dated July 18, 1882.

Application filed June 3, 1882. Term of patent 3½ years.

To all whom it may concern:

Be it known that I, WILLIAM H. CURRY, a citizen of the United States of America, residing at Baltimore, in the State of Maryland, have invented a certain new and original Design for a Souvenir, of which the following is a specification, reference being had therein to the accompanying drawing.

The drawing illustrates my newly-designed souvenir.

The object is to furnish a neat and tasty souvenir for the encampment of the "Grand Army of the Republic."

The leading feature of the design consists of a roll ornamented by colored bands and mounted on the top or upper narrow edge of a case provided with an ornamented cover hinged to the said upper edge.

The letter A designates the roll; B, the case, on the narrow upper edge, c, of which the roll is supported. The outer broad side, d, of the case comprises the cover, ornamented by gilt bands e, extending vertically. In the center of

the cover is an ornamental monogram, consisting of the letters "G. A. R." The colored bands f on the roll are ribbons, (red, white, and blue,) which pass around the roll into the upper edge of the case and out at the opposite lower edge, their ends f' dangling or projecting below. The lid, being partly open, exposes to view some rolls g, contained in the case.

I claim—

The design for a souvenir herein shown and described, the same consisting of a roll, A, ornamented by colored bands f and mounted on the upper edge of a narrow case, B, the broad side d of which is ornamented by vertical gilt bands e, and at the lower edge of the said case the dangling ends of colored ribbons.

In testimony whereof I affix my signature in presence of two witnesses.

WILLIAM H. CURRY.
